PILOT RESPONSIVE SAFETY CONTROL FOR
LIQUID FUEL BURNERS

Fred B. Aubert, Grosse Pointe, Mich.

Application December 2, 1943, Serial No. 512,551.

10 Claims. (Cl. 158—28)

1

This invention relates to new and useful improvements in control apparatus for liquid fuel burners and which is particularly adapted for the control of heavy fuel industrial burners.

An object of the invention is to provide such an apparatus in which the sequence of starting and of running operations is automatically supervised.

Another object is to render the starting of the burner dependent upon proper viscosity of the liquid fuel.

Another object is to provide means for checking the operation of the burner igniting means preliminary to the supplying of fuel to the main burner.

The invention consists in the cooperative relation of the control devices comprising the system or apparatus and in the devices themselves, the novelty of which will be more fully described hereinafter and will be particularly pointed out and distinctly claimed.

In the accompanying drawing to be taken as a part of this specification, there is fully and clearly illustrated a preferred embodiment of the invention, in which drawing the figure is a diagrammatic view showing a heating apparatus with its interrelated control devices and their interconnecting electrical circuits.

Referring to the drawing by characters of reference, 1 designates generally a heating apparatus such as a boiler or furnace for generating power, although it will be apparent that the installation may serve also or solely for space heating. The apparatus 1 has a combustion chamber 2 underlying or in heat exchange relation with the usual boiler water space or other chamber for containing a medium to be heated. The combustion chamber 2 is equipped with a fluid fuel burner 3 such as an oil burner having a combustion air supplying conduit or duct 4 fed with air under pressure from a blower 5 driven by an electric motor 6. Fuel such as oil, in combustible proportions with the air supplied by the blower 5, is supplied to the chamber 2 through a fuel supply pipe or conduit 7 having a spraying nozzle 8 discharging into the chamber 2, the pipe 7 having intercalated therein an electrically operated shut off valve 9 with an electromagnetic operating coil 10. The fuel is fed through the pipe 7 from a fuel supply source or tank (not shown) by a pressure pump 11 driven by the motor 6 through any suitable gearing or drive mechanism. Also in the length of the pipe 7 there is a fuel heating section or portion 12 which is positioned on the inlet side, but may be on the outlet side, of the

2

pump 11. The pipe section 12 has an electric heating means 13 which may be in the form of an electric resistance coil, preferably in direct heat exchange relation with the oil in the pipe 7 and which functions to increase the oil temperature and decrease the viscosity of the oil for its proper feeding to and through the nozzle 8. The combustible mixture of air and fuel discharged into the combustion chamber 2 is ignited by the flame from a gas or fluid fuel pilot burner 14 having the usual combustion air supply. Fuel is fed to the burner 14 through a pipe 15 having intercalated therein a shut off valve 16 which is electrically operated and controlled by an electro-magnetic coil 17. The gas mixture discharging from the pilot burner 14 is ignited by spark electrodes 18 supplied from the secondary coil of an ignition transformer 19 which has its primary coil 20 connected by lead wires 21, 22 to a source of current supply. Cooperable with the pilot burner there is a photo-electric cell or tube 23 contained in a box or casing having a light conducting sight tube or conduit 24 directed toward the pilot flame, the cell 23 being rendered conductive upon the impingement of light thereon resulting from the occurrence of flame at the pilot burner. The sight tube 24 provides a shield, protecting the pilot burner cell 23 against response to the light of the main burner flame. Cooperable with the flame from the main burner there is a photo-electric cell or tube 25 contained within a box or casing having a light conducting sight tube or conduit 26 directed toward the main burner flame, the cell 25 being rendered conductive upon the impingement of light thereon resulting from the occurrence of flame at the main burner. The main burner cell 25 is protected and shielded from response to the light of the pilot burner flame by the sight tube 26. The control system and heating apparatus is supplied with current from any suitable commercial or high voltage source through lead or service line wires 27, 28. The wire 27 is connected to the manually operated contact carrying switch arm 29 of a main control switch 30 which is manually movable into and out of electrical contacting engagement with a fixed contact 31 of switch 30 by means of a control handle or knob 32. Cooperable with the switch arm 29 there is an electromagnet or holding coil 33 which is of a strength only sufficient to hold the switch 30 closed against the force of a switch opening spring 34 acting on the arm 29. The fixed switch contact 31 is connected by a lead wire 35 to one terminal of the motor 6, the other motor termi-

nal being connected by a lead wire 36 to the service line wire 28. Connected to the motor lead wire 35 there is a lead wire 37 which connects to one terminal of the primary coil 38 of the main control system step down transformer 39 having a secondary coil 40. The other terminal of the primary coil 38 is connected by a lead wire 41 to the service line wire 28. Extending from the lead wire 37 there is a lead wire 42 which connects to one end or terminal of the heating means or resistance coil 13 which has its other end or terminal connected by a lead wire 43 to the service line wire 28.

The coil 33 of the main switch 30 is controlled by a pilot flame responsive electron tube relay switch 44 having a relay coil 45 and is also controlled by a safety relay switch 46. The relay coil 45 controls a normally closed single throw switch 47 having a contact carrying arm 48 and also controls a double throw switch 49 having a contact carrying arm 50. The switch arms 48, 50 of which one or both may cooperate with the coil 45 as armatures, are movable in unison and are preferably mechanically connected together by a link to assure simultaneous movement. The contact member of switch arm 48 is normally in engagement with its fixed switch contact 51. The double throw switch arm 50 has one of its contacts normally in engagement with a fixed switch contact 52 when in coil deenergized position and has its other contact normally open and operable to engage a fixed switch contact 53 upon energization of coil 45. The safety switch 46 has a relay coil 54 controlling a single throw switch 55 having a contact carrying switch arm 56 engaging its fixed switch contact 57, such that the switch 55 is normally closed when the coil 54 is deenergized. The relay switch 46 also includes a holding switch 58 with a contact carrying switch arm 59 cooperative with its fixed switch contact 60, the switch 58 being normally open when the coil 54 is deenergized. The arms 56 and 59 of which one or both may cooperate with the coil 54 as armatures, are movable in unison and are preferably mechanically connected together as by a link to assure simultaneous movement. The control of the main switch holding coil 33 by switch 55 of the safety switch 46 and by the double throw switch 49 of the electron tube relay switch 44 upon energization of transformer secondary coil 40 is through the following circuit: From one terminal of the transformer coil 40 via a lead wire 61 to the switch contact arm 50 of the double throw switch 49, through switch contact 52 and lead wire 62 to the fixed contact 57 of safety switch 55, thence through switch arm 56 and lead wire 63 to one terminal of the coil 33 and from the other terminal of coil 33 via lead wire 64 back to the other terminal of the transformer coil 40.

The oil delivery pipe section or portion 12 has in intimate heat exchange relation therewith a temperature responsive switch 65 which may comprise a bimetal actuator 66 in physical contact with the section 12 or with the oil therein and operable to move a contact carrying switch arm 67 into and out of engagement with a fixed switch contact 68. The temperature switch 65, when the oil gets up to temperature after closure of switch 30, controls the starting or running of a timer means 69 such as an electrically driven timing motor which drives a shaft 70 having fixed thereon an ignition controlling cam 71, a pilot burner controlling cam 72 and a main burner controlling cam 73, the cams being rotated in a clockwise direction facing the drawing as shown

by the arrows. The cam 73 has a cam lobe 74 angularly spaced from its follower member 75 so that a lapse of say twenty (20) seconds following energization of motor 69 occurs before lobe 74 actuates follower member 75. The follower member 75 of electric insulating material operates a normally open single throw switch 76 and a double throw switch 77. The switch 76 has a contact carrying resilient switch arm 78 mounted on a support 79 and connected to the follower member 75. The contact member of arm 78 is cooperable with a resiliently mounted fixed contact 80 carried by a switch blade secured to the support 79. The switch 77 has a contact carrying resilient arm 81 connected to the follower member 75 and mounted on the support 79, one contact member of arm 81 normally being in engagement and cooperable with a resiliently mounted fixed contact 82 carried by a switch blade mounted on the support 79. The other contact member of arm 81 is normally open and engageable with a resiliently mounted fixed contact 83, carried by a switch blade mounted on the support 79. The switches 76 and 77 and the contact supporting arms and blades thereof are electrically insulated from each other as by a mounting rod and spacer sleeves of insulating material. The follower member 75 is mechanically connected as by a pin and slot engagement to a pivoted armature 84 cooperative with a holding magnet 85. When the follower member 75 is moved by lobe 74 and closes the switch 76 and the arm 81 against contact 83, the armature 84 will be positioned in magnetic holding relation to the electromagnet 85. It is to be noted that the magnet 85 does not have sufficient strength to close the switch 76 and the switch contact 83, the cam lobe 74 being required to perform this operation. Upon closure of the temperature switch 65, the timing motor 69 is energized by the following circuit: From switch arm 67 through lead wire 86 to the switch arm 81 of the double throw switch 77, thence from closed contact 82 through lead wire 87 to the switch arm 48 of the single throw safety switch 47 of the tube relay switch 44, thence via switch contact 51 and lead wires 88, 89 and 90 in series to one terminal of the motor 69 and from the other motor terminal via lead wire 91 to the lead wire 64 which is connected to the transformer secondary 40 and thence from the transformer lead wire 61 through lead wire 92 to the oil temperature switch fixed contact 83. The timing motor lead wires 90 and 91 are connected respectively to and to feed the ignition transformer lead wires 21, 22 so that the ignition transformer 18 is energized upon closure of the temperature switch 65. The closure of switch 65 also energizes the electromagnet 83 to hold in cam operated position the follower member 85 of electric insulating material which is cooperative with a cam lobe 96 of the timing motor ignition pilot controlling cam 72, the magnet circuit being as follows: From lead wire 88 of switch 47 to lead wire 97 connected to one terminal of the coil of magnet 93 and from the other magnet coil terminal via lead wire 98 to lead wire 84 connected to secondary coil 40. The electromagnet 93 has insufficient strength to move its pivotally supported armature 99 from inactive position, the armature being operatively connected as by a pin and slot engagement with the follower member 85. Substantially instantly upon starting of the timer motor 69 and of initial rotation of the cam 71, which is preferably a circular disc having a

low point formed by an edge recess 100, the cam follower member 101 is forced or cammed out of the recess 100 into which the follower member 101 drops or moves upon a complete rotation of cycle of operation of the shaft 70. The follower member 101 operatively engages a resilient switch arm 102 mounted on a support member or structure 103 of electric insulating material. The arm 102 operates the normally opened switches 104, 105 having resiliently mounted fixed contacts 106, 107 respectively, the contact 107 being mounted by its resilient blade from the supporting member 103. Closure of switch 104 establishes a holding circuit for the main switch holding coil 33 as follows: From transformer lead wire 61 to lead wire 92, thence via lead wire 108, to switch arm 102 and from closed contact 106 via lead wire 109 to lead wire 63, connected to the coil 33 and thence back to the transformer via lead wire 64. Closure of switch 105 establishes a holding circuit for the timing motor 69 from the transformer lead wire 108 and switch arm 102 to the closed contact 107 and lead wire 110 to the motor lead wire 90. Since the lead wire 110 also connects to the lead wire 89 which is connected to lead wire 97, the holding magnet 93 of cam follower member 95 will be held energized upon opening of the pilot tube relay switch 47 as long as switch 105 remains closed. The switch 105, since it feeds lead wire 90, also establishes a parallel circuit for the ignition transformer 19 so that the ignition transformer will remain energized subsequent to the opening of the electron tube relay switch 47 and until the follower member 101 moves into its cam recess 100.

Subsequent to closure of switches 104 and 105, the cam 72 will rotate the cam lobe 96 into engagement with the follower member 95, there being preferably a lapse of say fifteen (15) seconds before the armature 99 is moved into holding relation with its coil 93 and the resilient contact carrying switch arm 111, mechanically connected to the follower member 95, is moved into engagement with its resiliently mounted fixed contact 112. The arm 111 and contact 112 comprise a pilot burner controlling switch 113 and are mounted on a supporting member or structure 114 of electric insulating material. Closure of switch 113 establishes a circuit for the gas valve coil 17 that feeds from the secondary coil lead wire 61 through lead wire 115 to switch contact 112 and thence via switch arm 111 and lead wire 116 to one terminal of the coil 17 and from the other coil terminal via lead wire 117 to the lead wires 98 and 64 connected to the transformer secondary coil 40. Opening of the valve 16 by energization of coil 17 will supply a combustible mixture of gas and air to the pilot burner 14 for ignition by the spark at the energized electrodes 18. The pilot flame will render the photo-cell 23 conducting and since the photo-cell 23 connects the control grid 118 of the electron tube 119 to ground via lead wires 120 and 121, the tube 119 will be rendered conducting and current will flow through the relay coil 45 of the tube relay switch 44. Energization of the coil 45 will operate the switch arms 48 and 50 to open the switch 47 and to break circuit at switch 49 with contact 52 and to make contact with contact 53. The opening of switch 47 has no effect upon the circuits initially closed thereby, as such circuits as above noted have been completed through additional switches. The opening of the switch 49 at contact 52 also has no effect upon the hold-

ing coil 33, as the holding coil circuit is also completed through the timer motor operated switch 104 as above described. Closure of contact 53 of double throw switch 49 establishes a preparatory circuit for the main burner and a holding circuit, hereinafter described, for the main switch holding coil 33.

The electron tube 119 forms part of an electrical network which is energized by a transformer 122 having a primary coil 123 connected by lead wires 124, 125 to the lead wires 37 and 41 respectively which are connected to the main service wires 27, 28 respectively. The tube 119 has an anode 126 connected by a lead wire 127 to one terminal of the coil 45, the other terminal of this coil being connected by a lead wire 128 to a transformer secondary coil 129 of the transformer 122. From an intermediate tap 130 of coil 129, to provide a plate voltage of say 142 v., there is a lead wire 131 connected to ground as at 132 and to the tube cathode 133 which is heated by a filament 134 energized at say 6 v. by the end turns or portion 135 of the coil 129. The extent to which the grid 118 must become positive is controlled by a shield grid 136 which is connected to the cathode filament return lead wire 136^a by a conductor 137 having a resistor 138 therein. The photo-cell lead wire 120 is connected by a lead wire 139 through a variable condenser 140 to the negative terminal of a secondary coil 141 of the transformer 122, the coil 141 having its positive terminal connected to ground as at 142. In the photo-cell lead wire 120 intermediate the control grid 118 and the lead wire 139 there is a resistor 143. The photo-cell lead wire 120 is also connected between the resistor 143 and the photo-cell by a lead wire 144 to balancing condensers 145, 146, which are connected respectively to the high voltage lead wires 124 and 125.

Upon the lapse of the above mentioned twenty (20) seconds interval which has brought the cam lobe 74 into operative engagement with the follower member 75, the follower member 75 will be actuated to close the fuel supply controlling switch 76 and to operate the double throw switch 77 to break circuit at contact 82 and to make circuit at contact 83 and also to move armature 84 into holding relation with the holding coil 85. Closure of switch 76 will energize the operating coil 10 of fuel valve 9 to open this valve for supply of fuel under pressure from the pump 11 to the burner nozzle 8, the circuit being as follows: From the now closed tube relay contact 53 via lead wire 147 to the cam switch contact 80, thence through switch arm 78 and lead wire 148 to one terminal of valve coil 10 and from the other valve coil terminal via lead wire 149 to lead wire 117.

The closure of the pilot flame switch contact 53 also completes a holding circuit for the main switch holding coil 33, as follows: From switch arm 50 to its closed contact 53, thence via lead wire 147 and lead wire 147^a to the lead wire 109 which is connected to lead wire 63 leading to the coil 33 as above described.

The combustible mixture of fuel and air discharging from the main burner into the combustion chamber 2 will be ignited by the flame from the pilot burner 14. Instantly upon the occurrence of the main burner flame, the photo-electric cell 25 will be rendered conducting, thereby rendering the electron tube 150 conducting by the connection of the control grid 151 to ground through lead wire 152 leading to the cell 25 which is connected to ground, as at 153. Energization of

the tube 150 will establish the circuit for a tube relay switch 154 having a magnetic relay coil 155 with one terminal connected by lead wire 156 to the electron tube anode 157. The other terminal of coil 152 is connected by lead wire 158 to one end of a secondary coil 159 of the electron tube network controlling transformer 160, the coil 159 preferably being tapped to provide a voltage of say 142 v. on the relay coil 155. The transformer 160 has a primary coil 161 connected in parallel with the transformer primary coil 123 and across the lead wires 124, 125. This electron tube 150 forms part of an electrical network substantially identical with the network of the tube 119, and, therefore, a detailed description is believed unnecessary. It may be noted, however, that the tube 150 has a shield grid 162, cathode 163 and heater filament 164. The relay switch 154 has switches 165, 166 with switch arms 167, 168 respectively, which are movable in unison and preferably mechanically connected together as by a link for simultaneous movement. The switches 165, 166 are normally open, the switch arm 167 being cooperable with a fixed contact 169 and the switch arm 168 being cooperable with a fixed contact 170. Upon closure of the switch 166 a circuit will be completed from the thermostatic switch 65 through the now closed contact 83 of the cam operated switch 77, the circuit being from contact 83 via lead wire 171 to the fixed contact 170 of switch 166 and through switch arm 168 and lead wire 172 to one terminal of the holding magnet 85 and from the other terminal of the magnet 85 through lead wire 173 to the lead wires 98 and 64 to the transformer secondary coil 40. The closure of switch 165 by coil 155 will establish a circuit from lead wire 171 through lead wire 174 to fixed contact 169 and thence through switch arm 167 and lead wire 175 to lead wire 147^a at lead wire 147 so that a circuit in shunt or parallel with the pilot flame switch contact 53 is established for the main switch holding coil 33. The lead wire 171 is also connected by a lead wire 176 to one terminal of the safety relay switch coil 54 so that when switch 55 is opened, the starting circuit for the coil 33 will be broken. The initial energizing circuit for coil 54 is therefore from transformer secondary 40 via lead wires 61 and 92 to the open switch 65. When the switch 65 is closed by desired oil temperature, the circuit continues thence through lead wires 86 to switch blade 81 of cam switch 77, to contact 83, and via lead wires 171 and 176 to one terminal of relay coil 54. The other terminal of coil 54 is connected by lead wire 177 to the lead wire 117 which is connected through the wires 98 and 64 to the other end of the transformer secondary coil 40. The lead wire 176 is also fed from a lead wire 178 connected to the fixed switch contact 60 of the holding switch 58 so that upon closure of switch 58 it will maintain its own holding circuit for coil 54 until transformer coil 40 is deenergized, the holding circuit being as follows: From lead wire 86 to a lead wire 179 connected to the switch arm 59, thence through closed contact 60 and lead wires 178, 176 to the holding coil 54, and therefrom via lead wire 177 as above recited.

The operation of the controlling system and apparatus is as follows: When heat is desired, the manually operated, magnetically held, main switch 30 is closed, which closes the following, heretofore described, high voltage circuits from line wires 27, 28, namely, the circuit to the motor 6 for driving the blower 5 and pump 11, the circuit to the oil heating resistor or element 13, and

the circuit to the primary coil 38 of the control system transformer 39. Energization of the transformer 39 energizes the holding coil 33 of the main switch 30 through the closed contacts of the double throw switch 49 of the pilot photo-cell relay 44 and through the closed contacts of switch 55 of the safety relay 46. This circuit for coil 33 is as follows: From the transformer secondary coil 40 through wire 61 to switch arm 50 and closed contact 52 of switch 49, lead wire 62 to closed contact 57 and arm 56 of switch 55, lead wire 63 to coil 33 and from coil 33 through wire 64 back to transformer coil 40. When the oil, heated by the energized element 13, reaches the desired degree of temperature for proper viscosity at which it will spray readily from nozzle 8 and mix with the air supplied from conduit 4, the bimetal element 66 closes its oil temperature switch 65 to close the circuit of the timer motor 69 through the closed single throw switch 47 of the pilot photo-cell relay 44 and through the closed double throw timer motor cam switch 77, the circuit being as follows: From transformer coil 40 through lead wires 61 and 92 to closed contact 68 and arm 67 of temperature switch 65, thence through wire 86 to cam operated arm 81 and closed contact 82, through lead wire 87 to arm 48 of switch 47 and its closed contact 51, thence through wires 88, 89 and 90 to the timer motor 69 and from motor 69 through wires 91 and 64 back to the transformer coil 40. The closure of temperature switch 65 also energized the pilot ignition transformer 19 which has its primary coil 20 in parallel or shunt with the motor 69, as above noted. The closure of the temperature switch 65 also closed the circuit of the gas valve cam switch holding coil 93 through the pilot tube relay switch 47 preparatory to operation of the pilot gas valve switch 113 by its timing motor cam 72, the circuit being as above described. Initial operation of the timer motor 69 acts through the timer motor controlling cam 71 to close the holding switch 105 which, as above described, completes a holding circuit for the timer motor and also establishes in parallel with the pilot flame relay switch 47, a circuit for the primary coil 20 of the pilot ignition transformer 19. Switch 105 also establishes a circuit for the holding coil 93 of the cam operated pilot valve switch 113, which circuit is in parallel with the circuit through switch 47. Substantially simultaneously with its closure of switch 105, the cam 71 also closes the holding switch 104 in parallel circuit with the pilot burner electron tube relay switch 49 for the main relay coil 33, the circuit being as above described. Continued operation of the timing motor 69 for a period of say 15 seconds rotates cam 72 to close the cam operated gas valve switch 113 which is thereupon held in closed position by the magnet 93, thereby completing the described circuit leading directly from the main transformer secondary coil 40 via wires 61 and 115 to and through switch 113 to the gas valve coil 17 to open the gas valve 16, the circuit thence leading directly back via lead wires 117, 98 and 64 to the transformer coil 40. If the gas mixture thus supplied to the pilot 14 is ignited by the ignition spark electrodes 18, the electron tube 119 controlled by the pilot photo-cell 23, responding to pilot flame, becomes conductive so that current flow therethrough energizes its tube relay coil 45 which breaks circuit at the single throw starting switch 47 for the timing motor 69 which, however, continues in operation due to its shunt circuit through its hold-

ing switch 105. The coil 45 also operates the double throw switch 49 to break the initial circuit for the main switch holding coil 33 which, however, is maintained energized by prior closure of its shunt circuit by operation of the holding switch 104 by the timing motor cam 71. Operation of the double throw switch 49 by coil 45 closes a circuit which branches, one branch leading from contact 53 via wires 147, 147^a, 109 and 63 to the main holding coil 33, and another branch closing from contact 53 a preparatory circuit 147, 80 to the open cam switch 76 for the oil valve 9. Continued operation of the timing motor for a period of say five seconds brings the oil valve switch operating cam 74 into operative position to move its follower member 75 to close its oil valve switch 76 which completes a circuit from the above mentioned branch circuit 147, 80 to the oil valve coil 10 via lead wire 148 and thence back via lead wires 149, 117, 98 and 64 to the transformer coil 40. Simultaneously with closure of switch 76, the follower member 75 breaks the timing motor starting circuit at switch contact 82, makes a controlling circuit at contact 83 and moves the armature 84 into holding relation with magnet 85. The fuel pump was started in operation simultaneously with the blower and since the heating element 13 has now brought the fuel to proper viscosity, oil will be discharged, the valve 9 being open, with the air into the combustion chamber 2 to provide a combustible mixture to be ignited by the gas pilot flame at burner 14. The occurrence of flame at the main burner is recognized by photocell 25 which becomes conducting, thereby rendering the electron tube 150 conducting to energize tube relay coil 155, which closes switches 165 and 166 which are supplied solely from contact 83 of cam switch 71. The main burner flame must occur during the one or two second interval while cam 74 is holding switch 77 closed at contact 83, because it is through this switch and the flame relay switch 166 in series that the holding coil 85 is energized. If flame does not occur at the main burner substantially instantaneously that the switch 76 is closed or before the oil valve cam 74 moves away from switch closing position, the main burner electron tube 150 will be blocked by the photocell 25, so that the tube relay 154 will be deenergized and accordingly, the oil valve switch 76 and the double throw switches 77, 83 will snap to open positions. Closure of flame relay switch 165 establishes a holding circuit for the main switch coil 33, so that the system will be maintained in operation when cam 71 releases switch 105. Switch 165 also establishes a circuit in parallel with the pilot tube relay switch contact 53, so that when cam 71 releases switch 105 to deenergize holding coil 93 for the pilot gas valve switch 113, a circuit for the oil valve 10 will be maintained closed. The main burner will now continue in operation until main switch 30 is manually opened, which will deenergize transformer 39 thus deenergizing holding magnet 85 so that the oil valve switch 76 will snap to open position, thereby cutting off the supply of fuel to the nozzle 8. If, during operation of the main burner there is a flame failure or if relay coil 155 is deenergized for any other reason, such as for example a short circuit or failure of photocell 25 or of electron tube 150, the switches 165 and 166 will open. Opening of switch 166 will deenergize holding magnet 85 so that the main burner valve switch 76 will open. Opening of switch 165 will deenergize the main switch hold-

ing coil 33, since its starting circuit through the safety relay switch 55 is open due to its coil 54 having been maintained energized by its holding switch 58 from temperature switch 65, even though the cam switch 71 at contact 83 is opened.

Having thus described the invention, what is claimed and is desired to be secured by Letters Patent of the United States is:

1. A fuel burner controlling apparatus comprising a main liquid fuel burner, a pilot burner for igniting said main burner, electrically operable means to supply liquid fuel to said main burner and having a controlling circuit, at least two switches in said circuit, means operable to close one of said switches upon occurrence of flame at said pilot burner, timing means to close for a short period the other of said switches to complete said controlling circuit, means to heat the liquid fuel to be supplied to said main burner, means responsive to the temperature of the heated fuel and operable to start operation of said timing means, electronic control means instantly responsive to flame at said main burner and operable to hold said other switch closed, and a switch in parallel circuit with said one switch and closed by said electronic control means in response to flame at said main burner.
2. A fluid fuel burner controlling apparatus comprising a main burner, means to supply fuel to said main burner and having a controlling circuit, two switches in series in said circuit, a pilot burner for igniting the fuel supplied to said main burner, means to supply fuel to said pilot burner, electrically controlled ignition means for the fuel supplied to said pilot burner, timing means, means to energize said timing means and said electrically controlled ignition means, pilot burner controlling means operable by said timing means subsequent to operation of said ignition means to render said pilot burner supplying means effective, means instantly closing one of said switches upon occurrence of flame at said pilot burner, and means controlled by said timing means subsequent to separation of said pilot burner controlling means and operable to close the other of said switches to render said main burner fuel supplying means effective.
3. A fluid fuel burner controlling apparatus comprising a main burner, means to supply fuel to said main burner, a pilot burner for igniting the fuel supplied to said main burner, means to supply fuel to said pilot burner, electrically controlled ignition means for the fuel supplied to said pilot burner, timing means, means to energize said timing means and said electrically controlled ignition means, pilot burner controlling means operable by said timing means subsequent to operation of said ignition means to render said pilot burner supplying means effective, means responsive to the occurrence of flame at said pilot burner, means controlled subsequent to the operation of said pilot burner controlling means and by the conjoint action of said timing means and said flame responsive means to render said main burner fuel supplying means effective, means operable by said timing means to stop operation of said pilot burner fuel supplying means, and means instantly operable in response to the occurrence of flame at said main burner to maintain operation of said main burner fuel supplying means upon operation of said last-named means to stop said pilot burner.
4. A fluid fuel burner controlling apparatus comprising a main liquid fuel burner, means to

11

supply liquid fuel to said burner, means to ignite the fuel supplied to said burner, means to heat the supplied fuel, means responsive to the temperature of the heated fuel, timing means started in operation by said responsive means, means operable by said timing means to actuate said igniting means, means operable by the conjoint action of said timing means and said igniting means to start said liquid fuel supplying means, and means responsive to occurrence of flame at said burner to maintain operation of said fuel supplying means.

5. A fluid fuel burner controlling apparatus comprising a main burner having a liquid fuel supply pipe, an electrically operable valve in said pipe and opened when energized for flow to said burner, an electric heating means for the fuel supplied by said pipe, a thermostatic switch responsive to the temperature of the fuel heated by said heating means and closed upon temperature increase, a timing motor energized by closure of said switch, a fluid fuel pilot burner for igniting said main burner, electric ignition means for said pilot burner and energized by closure of said switch, an electron tube rendered conductive by occurrence of flame at said pilot burner, a relay switch energized by current flow through said tube, an electrically operable valve controlling flow of fuel to said pilot burner, a switch controlling said pilot burner valve and closed for a short period by said timing motor, a magnetic holding coil for said pilot burner valve switch, said relay switch when de-energized having closed contacts establishing a circuit through said holding coil, a switch closed by said timing motor to establish a parallel circuit for said holding coil, a pair of switches closed by said timing motor for a short period subsequent to closure of said pilot burner valve switch, said relay switch having contacts closed upon its energization and controlling a circuit for said electrically operable main burner valve in conjunction with one of said last-named timing motor switches, a magnetic holding coil for said last-named pair of timing motor switches, an electron tube rendered conductive by the occurrence of flame at said main burner, a relay switch energized by current flow through said last-named tube and acting in conjunction with the other of said pair of switches to close the circuit for said last-named holding coil, and means to break the circuit of said last-named holding coil to stop operation of said main burner.

6. In a fluid fuel burner controlling apparatus, a burner, means to supply air and fuel to said burner, a main switch controlling said burner and urged to open position, electrically energizable means to hold said switch closed and energized upon closure of said switch, ignition means for said burner, means responsive to operation of said ignition means and operable to deenergize said energizable holding means, and means to start said ignition means and operable to establish for a predetermined period an alternate circuit to energize said energizable holding means.

7. In a fluid fuel burner controlling apparatus, a burner, means to supply air and fuel to said burner, a main switch controlling said burner and urged to open position, electrically energizable means to hold said switch closed and energized upon closure of said switch, ignition means for said burner, means responsive to operation of said ignition means and operable to deenergize said energizable holding means, means to start said ignition means and operable to establish for a

75

12

predetermined period an alternate circuit to energize said energizable holding means, means responsive to occurrence of flame at said burner, and means operable by said last-named responsive means to establish another circuit to energize said energizable holding means.

8. In a fluid fuel burner controlling apparatus, a liquid fuel burner, means to supply air and liquid fuel to said burner, a main switch controlling said burner and urged to open position, electrically energizable means to hold said switch closed and energized upon closure of said switch, ignition means for said burner, electric heating means energized by closure of said main switch and operable to heat the liquid fuel, timing means, a thermostatic switch responsive to the temperature of the heated fuel and operable to start said timing means, means operable by said timing means to establish for a predetermined period an alternate circuit to energize said holding means, means operable by said timing means during said period to start said ignition means, means responsive to operation of said ignition means and operable to deenergize said energizable holding means, and means responsive to occurrence of flame at said burner and operable to establish another circuit to energize said energizable holding means to maintain said burner in operation.

9. A fluid fuel burner controlling apparatus, comprising a main burner, electrically operable means to control the supply of fuel to said burner, a pilot burner for igniting said main burner, a solenoid valve controlling the supply of fuel to said pilot burner, electric igniting means for the fuel supplied to said pilot burner, timing means, a switch operable to energize said igniting means and to start said timing means, a pilot burner switch controlling said valve and closed by said timing means, means controlled by said timing means and operable to hold said pilot burner switch closed, cooperative switch means responsive to flame at said pilot burner and to operation of said timing means and operable to energize said electrically operable main burner supply means, and means responsive to flame at said main burner and operable to maintain energized said main burner supply means.

10. A liquid fuel burner controlling apparatus comprising a main fuel burner, a blower for supplying air to said burner, a pump for supplying liquid fuel to said burner, a motor for driving said blower and said pump, electric heating means for the fuel supplied by said pump, a gaseous pilot burner for igniting said main burner, an electric igniter for igniting said pilot burner, a main control switch biased to open position and having a magnetic holding coil, said switch when closed closing the circuit of its holding coil, of said motor and of said heating means, timing means having sequentially operated switches, a thermostatic switch responsive to the temperature of the heated fuel and operable at a predetermined temperature to energize said timing means and said igniter, said timing means acting to close for a predetermined time period one of its switches to establish a holding circuit for itself and an alternate circuit for said igniter and to close another of its switches to establish a holding circuit for said magnetic holding coil, a third timing means switch having a magnetic holding coil maintained energized by closure of said first-named timing means switch, a solenoid valve controlling fuel flow to said pilot burner and energized by closure of said third timing means switch,

an electron tube rendered conducting in response to flame at said pilot burner, a relay energized by current flow through said electron tube to open a closed switch in the starting circuit for said timing means, to open a switch in the initial circuit for said main switch holding coil and to close simultaneously a main burner controlling switch in parallel circuit with said second-named timing means switch to maintain circuit through the main switch holding coil, a solenoid valve controlled by said main burner controlling switch and controlling the discharge from said pump, a fourth one of said timing means switches being closed subsequent to closure of said timing means pilot burner switch and completing a circuit through said last-named solenoid valve from said main burner controlling switch, a magnetic holding coil for said fourth timing means switch, an electron tube rendered conducting in response to flame at said main burner, an electron tube relay energized by current flow through said last-named electron tube, a switch closed by energization of said last-named electron tube relay and cooperating with a fifth timing means switch closed upon closure of said fourth timing means switch, said last-named cooperating switches when closed completing a circuit through said

last-named magnetic holding coil, said last-named electron tube relay when energized closing another switch cooperable with said fifth timing means switch to establish a holding circuit for said main switch holding coil, a safety relay energized by closure of said fifth timing means switch and closing a holding circuit for its coil in series with said thermostatic switch, and a switch in the starting circuit for said main switch holding coil and opened by said safety relay.
